United States Patent Office

Des. 211,062
Patented May 14, 1968

211,062

MOVIE CAMERA

Albrecht Goertz, 9% Goertz Ltd., P.O. Box 711,
Nassau, Bahamas

Filed Mar. 13, 1967, Ser. No. 6,178

Term of patent 14 years

Claims priority, application Japan Oct. 20, 1966

(Cl. D61—1)

FIG. 1 is a front, side and bottom perspective view of a movie camera, showing my new design; and

FIG. 2 is a rear, opposite side and top perspective view thereof.

The drawing figures are stippled to indicate contrast in appearance.

I claim:

The ornamental design for a movie camera, as shown and described.
